UNITED STATES PATENT OFFICE.

CHARLES PETERSEN, OF HONESDALE, PENNSYLVANIA.

DESIGN FOR A SPOON, &c.

SPECIFICATION forming part of Design No. 20,816, dated June 2, 1891.

Application filed May 7, 1891. Serial No. 391,953. Term of patent 7 years.

To all whom it may concern:

Be it known that I, CHARLES PETERSEN, residing at Honesdale, in the county of Wayne and State of Pennsylvania, have invented and produced a new and original Design for the Handle of a Spoon or Fork, of which the following is a specification, reference being had to the accompanying drawing, forming part thereof.

10 The leading features of my design consist of the following elements: At the end of the handle is a side elevation of the first locomotive that was ever run upon a railroad in America; below this, upon a circular entablature, is a 15 front view of a lion's head, which appears in profile at the forward end of the locomotive. Below the lion's head are the letters "D. & H."

under which is inscribed the date, "August 8, 1829," and "Honesdale, Pa.," all arranged in horizontal lines. Lengthwise of the stem of the handle are the words "Stourbridge Lion;" but these inscriptions are not essential elements, and it is obvious may be changed or omitted without impairment of the described design for the handle of a souvenir fork or spoon.

20 What I claim is—

The design for a handle of a souvenir fork or spoon herein described, and illustrated in the drawing.

CHARLES PETERSEN.
